DESIGN FOR A GLASS

Edwin W. Fuerst, Toledo, Ohio, and Walter D. Teague, New York, N. Y., assignors to Libbey Glass Company, Toledo, Ohio, a corporation of Ohio

Application May 23, 1939, Serial No. 85,148

Term of patent 7 years

To all whom it may concern:

Be it known that we, Edwin W. Fuerst, a citizen of the United States, residing at Toledo, in the county of Lucas and State of Ohio, and Walter D. Teague, a citizen of the United States, residing at New York, in the county of New York and State of New York, have invented a new, original, and ornamental Design for a Glass, of which the following is a specification, reference being had to the accompanying drawing, forming a part thereof.

In the drawing:

Fig. 1 is a front elevational view of a glass showing our new design, the characteristic feature of which is the stem shown in full lines.

Fig. 2 is a sectional plan view taken along the line 2—2 of Fig. 1.

We claim:

The ornamental design for a glass, substantially as shown and described.

EDWIN W. FUERST.
WALTER D. TEAGUE.
